His Attorney.

UNITED STATES PATENT OFFICE.

HENRY GEISENHÖNER, OF SCHENECTADY, NEW YORK, ASSIGNOR TO GENERAL ELECTRIC COMPANY, A CORPORATION OF NEW YORK.

METAL-HEATING DEVICE.

1,299,931.

Specification of Letters Patent. Patented Apr. 8, 1919.

Application filed August 13, 1918. Serial No. 249,714.

To all whom it may concern:

Be it known that I, HENRY GEISENHÖNER, a citizen of the United States, residing at Schenectady, in the county of Schenectady, 5 State of New York, have invented certain new and useful Improvements in Metal-Heating Devices, of which the following is a specification.

The present invention comprises a new 10 method and apparatus for heating elongated objects, such, for example, as bolt blanks. It is the object of my invention to enable such objects to be heated uniformly and to a desired temperature either as a whole or over 15 a desired length.

It has been suggested to heat rivets by passage of current from a terminal making a butt connection with the head of a rivet to another terminal making contact with the 20 rivet shank but this method of heating results in the rivet head immediately adjacent the butt contact being heated to redness and even melted while the shank is still below red heat. A butt contact has so much higher 25 resistance than a clamped lateral contact that most of the heat is generated at the butt contact with consequent local overheating.

In accordance with my invention elongated 30 objects are heated by first passing current between contact clamps engaging laterally with the object and then passing current between a butt contact and a lateral contact. My invention includes also an apparatus for carrying out this process.

35 In the accompanying drawing Figure 1 is a side elevation of an apparatus embodying my invention; Fig. 2 is a top view; Fig. 3 is an end view of one set of clamping contacts, and Fig. 4 is an end view of a section 40 through lines 4—4 of Fig. 2, showing a set of contact clamps coöperating with the clamps shown in Fig. 3.

The apparatus shown in Fig. 1 comprises 45 a transformer consisting of a core 1, a primary winding 2, and a secondary winding 3 consisting usually of a single turn. This heating transformer is mounted on a base 4 and carries a framework 5 on which are mounted the various clamping devices for 50 holding the work and conveying a heating current thereto.

The apparatus is provided with duplicate 55 sets of contact clamps, so that two blanks may be heated alternately, one being replaced after having been brought to tem-

perature while the other is being heated. Only one blank is present in the apparatus at any one time, when the handle is in position III, hence one has been shown in dotted lines in the drawing.

As shown in Fig. 2, the blanks 6 and 7 are held respectively by the lateral contact clamps 8 and 9 movable in a vertical plane and by the lateral contact clamps 10 and 11 movable in a horizontal plane, the ends of 65 the blanks being adjacent the butt contacts 12 and 13. All of these contacts are operable by a single handle 14 pivoted at 15, as will be described later. As shown in Fig. 3 the movable jaw 16 of the clamp 9 is mounted on a lever 17 rocking on a pivot 18 and connected by means of a flexible conductor 19 to a plate 20. The movable jaw 16 coöperates with a stationary jaw 21. A spring 22 holds the jaws 16 and 21 apart, unless 70 they are forced toward each other by the cam 23 riding upon a roller bearing 24 attached to the jaw 16. Removable linings for these clamps to receive the wear are provided. The clamp 8 shown in an open position has the same construction.

As shown in Fig. 4 the clamps 10 and 11 each consist of two movable lever jaws 25, 26, pivoted respectively on pins 27, 28, near their centers. As best shown in Fig. 2, the links 85 29, 30 connect the lever jaws 25, 26, at their upper ends to a hinge block 31, which is in turn connected to a rod 32 sliding through a guide 33 fastened to the movable terminal plate 13 (Fig. 1). In Fig. 2 the rod 32 connected to the lower clamp has been shown in part broken away. This rod 32 is connected to reciprocating mechanism, as will be explained later, to operate the jaws 25, 26.

The butt contact 13 carries a rod 35 which 90 is fixedly attached at one end to the guide 33 and at the opposite end to the bracket 36. Mounted upon the rod 35 is a spring 38, one end of which is connected to the rod 35 by an adjusting nut 39, and is connected at the 100 opposite end to a block 40 slidably mounted upon the rod 35. The block 40 is in turn linked to a lever 41 by a pin 42 passing through a slot in the lever 41. The lever 41 is movably pivoted at one extremity by a 105 pin 43 to a bracket 44 which is attached to a plate 45 constituting a transformer terminal. The lever 41 is movably pivoted at the opposite extremity to a rod 46, which is in turn connected to the handle 14. The block 40 is 110

connected through a gear rack and double segment lever 47 to the corresponding block 40' upon the opposite side of the device which is mounted upon a corresponding rod 35' connected to the bracket 33'. As the rod 32 has been shown broken away in Fig. 2, the construction may be better understood by reference to the connection of the corresponding rod 32' to the block 40'.

19 It will be observed that a movement of the handle 14 through a vertical arc causes the block 40 upon one side to move in one direction and the block 40' on the opposite side to move in the opposite direction. The contact plate 13 is mounted on pivots 48, 48', permitting lateral motion and is provided with a removable plug-shaped contact 49 which makes contact with the blank to be heated. This plug 49 may be easily replaced 20 when worn by use without disturbing the entire mechanism.

In the position I of the handle 14 (Fig. 1) the lateral contacts 9 and 11, and the butt contact 13, are closed and the opposite contacts 8, 10 and 12 are open. The sequence of operations may be better understood by considering the handle 14 in position III. All the contacts are then open. A blank may then be inserted in contacts 9, 11 and 13, and 30 another removed on the opposite side. The handle is then moved into position I closing contacts 9 and 11, and moving the butt contact 13 against the end of the blank by compressing the spring 38. The handle is then 35 moved back to position II. The contact 9 remains closed but the contact jaws 11 open up. The contact 13 remains pressed against the end of the rod 6 by the spring 38, the tension of which is not entirely released.

40 At the beginning of the described operation, therefore, the blank 6 is given a preliminary heating between contacts 9 and 11. The contact clamps 11 are connected to the plate 13 which in turn is connected to one 45 terminal of the transformer secondary 3 by the flexible leads 50, the contact 13 and the flexible lead 51. When the handle 14 is moved back to position 2 and the contacts 11 are drawn away from the blank 6, which 50 may be assumed to be at a dull red heat, current passes between the butt contact 13 and the lateral clamping contact 9, completing the heating of the blank by bringing the end adjacent the butt contact up to temperature 55 and raising this part of the blank as well as the remaining section between the contacts up to the required temperature. The handle is then moved back to position III. Another blank is inserted into contacts 8, 10 and 12 60 and the handle 14 moved to position V. In this position the contacts 8, 10 and 12 are closed while the contacts 9, 11 and 13 remain open. The heated blank is then removed. The cycle above described is then repeated 65 with reference to the blank 7, current first

passing between the clamping contacts 8 and the contacts 10, as well as the butt contact 12, to give the blank a preliminary heating, and the handle then being moved back to position IV to open the lateral clamping contacts 10 and to complete the heating by a current passing between the contacts 8 and the butt contact 12.

The various contacts are preferably water cooled by making the rods 35 and 35' hollow 75 to convey a cooling fluid, such as water, which flows through the ducts in the butt contacts 12 and 13, as indicated by dotted lines, and then flows through the clamping contacts 10 and 11 through the hollow supporting pins 27 and 28 and 27' and 28', and finally flows over the exterior of the contact jaws 25, 26, into a pan 53 from which it is discharged through opening 54. The contact clamps 8 and 9 are cooled by a fluid 85 supplied through tubes 55 and 56 water flowing through the ducts, indicated by dotted lines in Fig. 3 and flowing over the exterior of the contact jaws into the pan 53.

The length of the section of the blank 90 which is being heated may be varied by moving the contacts 8 and 9 toward and away from the contacts 10 and 11. The lower ends of these contacts are attached to clamping bolts 57 sliding back and forth within 95 slots 58 in the framework 5, and adapted to be fastened in any desired position by the nuts 59 shown in dotted lines, in Fig. 1.

What I claim as new and desire to secure by Letters Patent of the United States, is:— 100

1. The method of heating an elongated metal body which consists in passing a preliminary heating current between a lateral contact near an end of said body and a more remote contact and thereupon continuing the current input at said end from a butt contact. 105

2. The method of heating an elongated metal body which consists in first heating said body between a region of current input 110 at and about an end of said body and a more remote contact, thereupon increasing the current density at said end by restricting the contact area to a butt connection, and continuing the heating by passage of current from said butt contact until a desired temperature has been attained. 115

3. A metal heating device comprising the combination of a pair of work-engaging contact clamps, means for causing said 120 clamps to engage with work to be heated, a third coöperating contact and means for holding said third contact into engagement with the work and simultaneously disengaging from the work one of the paired 125 contacts.

4. A metal heating device comprising the combination of a pair of work-engaging contact clamps, a lever having a cam surface engaging with one of said clamps, links 130

connecting another of said contacts with said lever, a third coöperating contact, and means for holding said third contact into engagement with work held by one of said pair of contacts while the other is disengaged from the work.

5. An apparatus for heating an elongated conductive object which consists in the combination of a heating circuit, two contact clamps connected to said circuit for laterally engaging an object to be heated, a contact also connected to said circuit for making a butt connection with said object, means for causing said lateral contact clamps to grasp an object to be heated and convey a heating current therethrough, means for retracting one of said clamps nearer the butt contact, means for exerting pressure between

said object and said butt contact while the adjacent lateral contact is retracted. 20

6. A metal heating device comprising the combination of work-engaging contacts adapted to laterally engage work to be heated, a butt contact connected in common with one of said lateral contacts, a lever 25 having a cam surface engaging with one of said contacts to operate the same, links connecting another of said lateral contacts with said lever and movable thereby into engagement with the work, and means for exerting pressure upon the work by said butt contact by said lever while disengaging the work from said second lateral contact.

In witness whereof, I have hereunto set my hand this 12th day of Aug., 1918.

HENRY GEISENHÖNER.
